D-5730

5,730

UNITED STATES PATENT OFFICE.

NICHOLAS MÜLLER, OF NEW YORK, N. Y.

DESIGN FOR CLOCK-FRONTS.

Specification forming part of Design No. 5,730, dated March 26, 1872.

To all whom it may concern:

Be it known that I, NICHOLAS MÜLLER, of the city, county, and State of New York, have invented a new and ornamental Design for a Clock-Front; and I do hereby declare that the following is a full, clear, and exact description thereof, which will enable those skilled in the art to make and use the same, reference being had to the accompanying photographs forming part of this specification, in which the design is represented by a front view.

This design is composed of two parts—the main or upper part, and the base or lower part—indicated respectively by the letters A A and B B. The part A A consists of two columns supporting the arched Gothic top piece of the design, said top piece containing a star-shaped central ornament, from which again proceed graceful curves and foliage.

The space between the columns is occupied by the dial D, and a large Egyptian ornament, as seen in the photograph. The base B B is shaped and embellished in accordance with the other part of the design, the main feature being a series of ornaments in relief.

I do not claim the design of the two columns in the part A A.

What I claim as my invention, and desire to secure by Letters Patent, is—

The part B B, and the part A A, excepting the two columns therein, of the design for a clock-front, as herein shown and described.

Signed by me this 25th day of January, 1872.

NICHOLAS MÜLLER.

In presence of—

J. P. AECKERSBERG,
CHARLES KITSRETT.
